ATTACHMENT FOR RECORD PLAYERS AND
OTHER COIN CONTROLLED MACHINES

Roy E. Harris, Racine, Wis.

Application August 24, 1953, Serial No. 375,941

1 Claim. (Cl. 340—162)

This invention appertains broadly to annunciators, and more particularly to a novel attachment for coin controlled record players, juke boxes and other like machines, to stimulate the playing thereof by patrons of a public place.

In coin controlled record players, a customer can select a record to be played that he desires, and in order to add interest to the playing of the machine, it is one of the primary objects of this invention to provide means whereby the attendant of a public place in which the record player is located can select (unknown to the patrons) a record, as the mystery tune of the hour or day, as the case may be, and when a customer plays the selected record suitable annunciators make known this fact to all persons in the establishment.

Another salient object of my invention is to provide an electrical attachment for coin controlled record players and the like embodying a master selector switch under the control of an operator of an establishment for placing in circuit any desired record, so that upon the selection of the record by a customer visual or audible signals will announce this fact to the public assembled.

A further object of my invention is the provision of a plurality of circuits controlled by the movement of a record into and out of playing position with a master selector switch for rendering a desired circuit operative upon the playing of one certain record to bring about the actuation of any desired type of signal.

With these and other objects in view, the invention consists in the novel construction, arrangement and formation of parts, as will be hereinafter more specifically described and claimed and illustrated in the accompanying drawing, in which drawing, the figure is a schematic view illustrating the wiring diagram for my attachment for an automatic record playing machine.

Referring to the drawing in detail, the letter A generally indicates my novel attachment for a coin controlled automatic record playing machine M. All parts have been shown diagrammatically as stated above, and only a sufficient showing of the machine M has been illustrated to bring about the necessary understanding of the invention.

The record player M is of the type embodying a plurality of records 5 which are movable into and out of playing position upon the depositing of a coin and the selection thereof by a patron. In the drawing, I have only shown 5 records, with 4 of these records in their non-playing position and the 5th record being moved to its playing position, and it is to be understood that in actual practice, the record player holds from 24 to 50 records, depending upon its make.

My attachment A comprises a master selector switch 6 and a switch 7 for each record to be played. Where the machine M contains a great number of records then, if desired, a switch 7 can be provided for say, every 5th record.

The master selector switch 6 includes a panel 8 having two spaced rows of contacts 9 and 10, with each row of

contacts arranged in an arc of a circle and the panel can be formed from dielectric material. Mounted on the panel for turning movement is a manually operable selector member 11 including oppositely extending conductor switch arms 12 and 13. These switch arms are insulated one from the other by a dielectric hub 14 and upon the turning of the hub, the arms 12 and 13 can be moved into contact with selected contacts of the rows 9 and 10.

10 All of the record operated switches 7 are mounted upon a panel strip 15 located in close proximity to the records 5 to be played. The switches are all of identical form and each include stationary contact leaves 16 and 17 provided respectively with contact points 18 and 19. Between the stationary leaves 16 and 17 is mounted a movable resilient switch leaf 20 carrying on its opposite sides contact points 21 and 22. The forward outer end of the leaf is curved to provide a guide leg 23 which is adapted to be engaged by a record disposed in a non-playing, non-selected position. The movable leaf 20 is so tensioned, as to normally bring its contact 22 in electrical engagement with the contact 19 of a stationary leaf 17. When a record is in its non-playing position the record engages the leg 23 and moves the leaf 20 away 25 from the leaf 17 and toward the leaf 16 to bring the contact 21 into electrical engagement with the contact 18 of the stationary leaf 16.

Now referring to the wiring for the master selector switch 6 and the various record switches 7; current is derived from any suitable source such as a house circuit indicated by the reference character C, in which instance a transformer 24 can be employed for lowering the voltage. Lead wires 25 and 26 are electrically connected to the transformer and the wire 25 leads directly to and is 30 electrically connected with the arm 13 and the master selector switch member 11. Interposed in the length of the wire 25 is a suitable signal, such as an electric light 27. The lead wire 26 extends toward the record switches 7 and is electrically connected with the movable leaf 20 35 of each switch 7 by a branch wire 28. Connected with the contacts of the row of contacts 10 are independent conductor wires 29, and these wires are electrically connected with the leaves 16 of the switches 7—it being understood that one wire 29 leads to one leaf 16 of a certain switch 7.

Considering that all of the records are in a non-playing position, then all of the leaves 20 of the switches 7 will be flexed so that the contacts 18 and 21 are in engagement and in which instance, current flow will be through 50 wire 25, lamp 27, switch arm 13, a selected contact of the row of contacts 10, wire 29, leaf 16, contacts 18 and 21 of a selected switch 7, branch wire 28 back through wire 26 and the lamp 27 will be constantly illuminated until the mystery tune selected by the operator of an establishment is played by a patron.

Leading from the contacts of the row of contacts 9 are independent conductor wires 30 and these wires are electrically connected respectively to the switch leaves 17 of the switches 7.

60 Electrically connected with the arm 12 of the master selector switch member 11 is a conductor wire 31 which leads to and is electrically connected to the lead wire 25 adjacent to the transformer 24. Interposed in the length of the wire 31 is a suitable annunciator such as a buzzer 32. It is to be understood that this annunciator can be of any type or character, such as a bell, buzzer, horn, etc. In fact, a record player could be substituted for the buzzer 32 so that the announcement of the playing of the mystery tune could be made by a voice reproduction. 65 70 In operation of my attachment the master selector switch is placed at a point distant from the coin controlled record player, and preferably back of a bar or

the like. The operator of the establishment now moves the switch so that the arms 12 and 13 will contact selected contacts of the rows of contacts 9 and 10 (see drawing). When a patron plays the record selected by the operator of the establishment, the record moves from its non-playing position to its playing position and releases the movable leaf 20 of its switch 7, at which time the circuit through the lamp 27 is broken and the light goes out. Simultaneous with this operation, a circuit is closed through the annunciator or buzzer 32 and this sound informs the public that the patron has located and played the mystery tune of the hour or day, as the case may be.

The current flow is as follows: through wire 25, annunciator 32, wire 31, switch arm 12, selected contact of the row of contacts 9, through selected wire 30, to leaf 17 of the selected record switch 7, contacts 19 and 22, switch leaf 20, and wire 26 back to the transformer.

While my attachment has been particularly designed for coin controlled record players, it is to be understood that the attachment can be successfully used with other coin controlled machines, such as pin ball machines, bowling machines, etc., and in this instance, the master selector switch will be actuated by the operator of an establishment to pick out a certain score as the mystery score for the hour or day.

Changes in details may be made without departing from the spirit or the scope of this invention, but what I claim as new is:

An attachment for coin controlled record players comprising independent switches for the records of the player adapted to be actuated by the movement of the records from playing to non-playing positions, each of said switches including spaced stationary contacts and an intermediate movable leaf adapted to electrically contact either one of the stationary contacts according to the position of a record, independent circuits for one stationary contact of the switches, independent circuits for the other stationary contacts of the switches, a master switch for selectively completing any one of the circuits associated with a contact which is contacted by the corresponding intermediate contact when the corresponding record is in the non-playing position and simultaneously preparing the circuit for the associated contact which is contacted by the same intermediate contact when the same record is in playing position, and two separate signals, one for each set of circuits.
